UNITED STATES PATENT OFFICE.

BENOY BHUSHAN RÄHÄ, OF CALCUTTA, BRITISH INDIA.

REVERSIBLE REACTION-TYPE STEAM TURBINE.

Application filed June 11, 1920. Serial No. 388,278.

To all whom it may concern:

Be it known that I, BENOY BHUSHAN RÄHÄ, a subject of His Majesty King George V, and a resident of Calcutta, British India, have invented Improvements in or Relating to Reversible Reaction-Type Steam Turbines, of which the following is a specification.

This invention relates to a new type of steam turbine in which a cylindrical boiler is mounted on a shaft and rotates therewith, said boiler carrying or having connected to it a plurality of nozzles adapted to direct the discharging steam against a fixed surrounding ring consisting of a series of reaction blades, the steam impinging against said blades and by the reaction driving the shaft.

Two sets of nozzles, adapted to drive the turbine in opposite directions, are employed, together with means whereby one or the other set may be connected to the steam supply, thus providing a reversible turbine, which, by suitably shaping the curves of the reaction blades, may be as efficient when working in either direction. The boiler, being mounted on the turbine shaft, acts as a fly wheel. Water or steam is introduced through the shaft, which is made hollow for that purpose, and enters the boiler by a series of perforations in the shaft and may be sprayed through said perforations onto the bottom or sides of the boiler or onto baffle plates fixed therein. These baffle plates increase the heating surface and also prevent priming, and they further provide a compartment towards the steam exit end of the boiler wherein the steam may be superheated.

The nozzles may be fitted in cavities formed in a nozzle ring, or, alternately, may consist of series of projecting nozzles fixed to the ring. In the latter case, they may have enlarged portions wherein the steam may be further superheated before being finally used.

My invention may be adopted for use in a stationary turbine with a vertical main shaft, or it may, if preferred, be applied to a locomotive or other type with a horizontal shaft.

The invention will be described with reference to the accompanying drawings in

which like numerals refer to like parts throughout, and in which:

Figure 1 is an elevation of the stationary type of turbine with a vertical shaft;

Figure 2 is a plan of the same;

Figure 3 is a side elevation of one of the nozzles used;

Figure 4 is an elevation of a locomotive type with horizontal shaft;

Figure 5 is a part section showing a different type of nozzle;

Figure 6 is a diagram showing how the turbine may be reversed;

Figure 7 is a detail of one of the nozzles represented in Fig. 5;

Figures 8 and 9 show the locking means whereby the nozzles can be locked in one of their three positions, viz: forward, neutral and reverse; and

Figure 10 illustrates means whereby the nozzle ring may be rotated relatively to the shaft to take up a desired position.

The invention will be first described with reference to the type of turbine with vertical main shaft.

The shaft 1 is carried on a suitable frame 2. On this shaft the boiler 3 is mounted and rotates with the same.

The boiler which is partially enclosed in or surrounded by the furnace 4 may be of the flash type.

Water is introduced into the boiler through the feed pipe 5 and passes up through the centre of the shaft being sprayed out through holes 6 in the shaft as shown by the arrows.

The water or steam is sprayed out through these holes under pressure and the spray falling on the walls of the boiler will immediately be turned into steam. If excess of water is introduced the centrifugal action will keep the water against the outer walls of the boiler. The lower holes in the shaft may be inclined downwardly so that some of the water will certainly be sprayed against the bottom 7 of the boiler as indicated by the arrows *a, a'*, Fig. 1, to prevent over heating.

Baffle plates 8 may be fitted in the interior of the boiler to prevent the water rising too high against the walls under the centrifugal action and for the purpose of pre-

venting priming. These baffle plates also increase the heating surface.

When only sufficient water is being introduced to flash into steam before or upon falling on the walls of the boiler a certain amount of super-heat may be given to the steam.

The shaft 1 is mounted on suitable bearings 9 and 10 and convenient lubricating means 11 may be provided.

A series of nozzles or jets 12, 12^A are mounted on a ring 13 surrounding the boiler 3. These nozzles are arranged alternately half for driving the turbine in a clockwise direction and the other half for reversing the direction of rotation. In the Figure 2 the nozzles 12, 12 are for the former purpose, and nozzles 12^A, 12^A for the latter, it being supposed that there are four of each.

The ring 13 on which the nozzles are mounted is capable of rotation relatively to the boiler, suitable means being provided for such rotation and to lock the nozzle ring and boiler in desired positions.

Corresponding to the passages in the nozzles there are holes 14 in the boiler casting. The number of such holes in the boiler is just half of the number of nozzles, which themselves are even in number.

The nozzle ring fits closely to the boiler so that only that series of nozzles which are opposite the holes in the boiler will come into action. When the jet or nozzle ring is rotated into a position where the holes are blind all steam will be cut off, and the turbine will stop rotating.

The steam from the nozzles impinges on a series of blades or teeth 15 of suitable shape formed on the inner surface of the blade ring 16. The angle at which these blades are placed and the shape of these blades is such as to give the maximum efficiency possible in this type of turbine according to modern theories of design.

The steam after expending its energy on the blades passes upwards to the exhaust or to the condensers if such are fitted.

The nozzles used may be of a special shape having an enlarged portion 17 which forms a receptacle for the steam. These enlarged portions rotate in a belt of hot gases rising from the furnace and the steam obtains a slightly higher degree of super-heat whilst passing through such enlarged portions.

Suitable fast and loose pulleys 19 and 20 may be fitted to the shaft to transmit the power by belting to machines or to shafting.

A modification of my invention is shown in Figures 4 to 10. In this the shaft 1' is horizontal and carries a long cylindrical boiler 3' fixed thereto. The furnace 4' surrounds the boiler completely.

The feed water is forced through the hollow shaft and sprayed through holes 6', 6' therein onto the sides of the boiler and onto

a series of baffle plates 8', 8' fitted inside the same. Some of these baffle plates may, if preferred, be perforated.

The feed water enters generally from the end, at which the furnace door 21 is shown. As the steam approaches the funnel 18 or smoke stack end of the furnace it is superheated.

In this alternative method the nozzles or jets act in exactly the same manner as in the previous method described, but the nozzles themselves are made in a different manner. The nozzle ring 13' is a solid ring of considerable thickness which has cavities or holes 21' made in it, to take the nozzles 12, or 12^A. These cavities are provided with a screw thread into which the nozzles themselves screw. The ends 22 of the cavities are suitably curved or shaped so that the steam reacts against such curved surface and is deflected in a straight path out of the orifice of the nozzle.

To allow the nozzles to be screwed into their cavities 21' they may be provided with suitable notches or holes 23, 23 to fit a spanner or other turning means.

To lock the nozzle ring to desired positions suitable means may be provided. One such type of means is illustrated in Figures 8 and 9. According to these means the end of the boiler 3' is provided with three catches 24, 25 and 26. The nozzle ring is provided with a latch 27 pivoted at 28. The end 27^A of the latch is designed to engage one or other of these catches 24, 25 or 26. When the latch 27 engages the catch 24 the nozzle ring is set in the position to drive the turbine in a clockwise direction; when it engages catch 26 in an anti-clockwise direction, and when in the central catch 25 the nozzle ring is so set that all steam to the nozzles is cut off.

To disengage the locking device above-mentioned the lever 29 pivoted at 30 is provided. At the end of this lever a contact wheel 31 or rounded knob may be fitted, and when the lever is depressed, this wheel is brought into position to engage a ramp 32 on a rear extension 33 of the latch 27 during the rotation of the boiler, so as to press down said extension 33 and thus lift the blade 27^A of the latch out of the catch with which it is engaged. By such means the locking device may be automatically disengaged while the turbine is running at full speed and the nozzle ring then being free to rotate relatively to the turbine shaft will by such movement cut off steam to the nozzles and tend to bring the turbine to rest. Arrangements would have to be made at the same time to bank the fire or if oil fuel was being used to cut off the supply of such fuel so that the boiler should not get burnt. The boiler may be provided with suitable safety valve 34 and gauge 130

glass 35. These fittings rotate with the boiler.

The gauge glass is not of the tube type, but is a thick pane of glass let into the end 5 of the boiler through which the level of the water in the boiler can be ascertained by rotating the boiler until such gauge glass is at the bottom.

To set the nozzle ring to drive the turbine 10 in the desired direction the device shown in Figure 10 is used. In this device a toothed rim 36 may be provided on the nozzle ring. A pinion 37 adjustably mounted on a frame 38 fixed to the stationary part of the turbine 15 bine is designed to engage such toothed rim. This pinion may be made to engage or disengage by means of a hand wheel 39 and screwed shaft 40 moving the pinion in guides in the frame 38. When in engage- 20 ment the pinion may be rotated by means of the handle or lever 41, thus moving the toothed wheel 36 and the nozzle ring 13' until the desired catch 24 or 26 is opposite the fastening device 27.

25 In the locomotive type of turbine motion might be conveyed from the shaft to the driving wheels or to machinery by means of a belt or chain fixed to the pulley or chain wheel 42, or it may be connected direct to a screw propeller.

It will of course be understood that certain modifications may be introduced without departing from the essential features of my invention. For instance, although I 35 use an even number of nozzles this is not essential. If for any reason it is not necessary for the turbine to work backwards with as much power as in the forward direction only half as many reversing nozzles 40 might be mounted as forward driving ones. In such case the nozzles would not necessarily be even in number and the number of holes in the boiler might correspond in that case to the number of forward driving noz- 45 zles, some of such holes being closed or blind when the nozzle ring is fixed to drive in the reverse direction.

I may if I prefer use low pressure steam in the boiler part shown, using a separate 50 boiler for supplying such steam. The boiler shown as a part of the turbine would then become a superheater only.

By a suitable positioning of the means for fastening the nozzle ring relatively to 55 the holes in the boiler these holes may be full open, partially opened or closed. When the holes are only partially open the use of the steam is economized and the turbine may be used working only partially 60 loaded.

In the type of turbine with a horizontal shaft the steam or water is forced into the boiler part 3' through perforations in the hollow shaft only for a certain portion at 65 the entry end of the same.

Opposite this perforated portion a series of baffle plates may be fixed which themselves may be perforated. These baffle plates increase the heating surface. Beyond the portion where the water or steam 70 is introduced the baffle plates are unperforated and divide the boiler part into several different chambers connected together by the annular spaces around the shaft left by such baffles. The object of these chambers is to super-heat the steam. The number of these chambers may be increased to allow for higher super-heat.

A brake may be fitted to bring the turbine to a dead stop when desired.

Having now particularly described and ascertained the nature of my said invention and in what manner the same is to be performed, I declare that what I claim is:—

1. A turbine comprising a rotary carrier; a nozzle ring rotatably mounted on said carrier; two sets of nozzles carried by said ring, one set for each direction of rotation; blades cooperative with the nozzles; means for rotating the nozzle ring to position 90 either set of nozzles for connection with the steam supply or to shut off both sets therefrom; means for locking said ring in any one of its three positions; and manually controlled means for automatically releasing 95 the locking means while the turbine is running.

2. A turbine comprising a rotary carrier; a nozzle ring rotatably mounted on said carrier; two sets of nozzles carried by said ring, 100 one set for each direction of rotation; blades cooperative with the nozzles; a toothed rim on said ring; and a pinion mounted on a stationary part of the turbine and meshing with said rim to rotate the nozzle ring 105 to connect either set of nozzles with the steam supply or to shut off both sets therefrom.

3. A turbine comprising a rotary carrier; a nozzle ring rotatably mounted on said 110 carrier; two sets of nozzles carried by said ring, one set for each direction of rotation; blades cooperative with the nozzles; a toothed rim on said ring; a pinion mounted on a stationary part of the turbine and 115 adapted to mesh with said rim to rotate the nozzle ring and thereby selectively connect either set of nozzles with the steam supply or shut off both sets therefrom; and means for moving said pinion into or out of mesh 120 with said rim.

4. A turbine comprising a rotary carrier; a nozzle ring rotatably mounted on said carrier; two sets of nozzles carried by said ring, 125 one set for each direction of rotation; blades cooperative with the nozzles; means for rotating the nozzle ring on the carrier to position either set of nozzles for connection with the steam supply or to shut off both sets therefrom; a catch for each of the three 130

positions of the ring; a latch engageable selectively with said catches to lock the ring in any one of said positions; and a device engageable with said latch to release it from such engagement.

5. A turbine comprising a rotary carrier; a nozzle ring rotatably mounted on said carrier; two sets of nozzles carried by said ring, one set for each direction of rotation; 10 blades cooperative with the nozzles; means for rotating the nozzle ring on the carrier to position either set of nozzles for connection with the steam supply or to shut off both sets therefrom; a catch for each of the three 15 positions of the ring; a latch engageable selectively with said catches to lock the ring in any one of said positions; and a manually controlled device for automatically releasing said latch from such engagement while the 20 turbine is running.

6. A turbine comprising a rotary carrier; a nozzle ring rotatably mounted on said carrier; two sets of nozzles carried by said ring, one set for each direction of rotation; blades 25 cooperative with the nozzles; means for rotating the nozzle ring on the carrier to position either set of nozzles for connection with the steam supply or to shut off both sets therefrom; a catch for each of the three 30 positions of the ring; a latch engageable selectively with said catches to lock the ring in any one of said positions; and a releasing member adapted to be positioned in the path of said latch to engage the latch and thereby move it out of such engagement.

7. A turbine comprising a rotary carrier; a nozzle ring movably mounted on said carrier; two sets of nozzles carried by said ring, one set for each direction of rotation; 40 blades cooperative with said nozzles; means for adjusting said ring to position either set of nozzles for connection with the steam supply or to shut off both sets therefrom; means for locking said ring in any one of 45 its three positions; and manually controlled means for automatically releasing said locking means while the turbine is running.

8. A turbine comprising a rotary carrier; a nozzle ring movably mounted on said carrier; a set of nozzles carried by said ring; blades cooperative with said nozzles; means 50 for adjusting said ring relatively to said carrier to bring the nozzles into or out of position for connection with the steam supply; means for locking said ring in adjusted position; and manually controlled means for automatically releasing the locking means while the turbine is running.

9. A turbine comprising a rotary carrier; 60 a nozzle ring movably mounted on said carrier; two sets of reversely-inclined nozzles carried by said ring, one set for each direction of rotation; a single set of blades cooperative with both sets of nozzles; means 65 for adjusting said ring relatively to the

carrier to position either set of nozzles for connection with the steam supply; means for locking said ring in adjusted position; and manually controlled means for automatically releasing said locking means while the turbine is running.

10. A turbine comprising a rotary carrier; a nozzle ring movably mounted on said carrier; two sets of reversely-inclined nozzles carried by said ring, one set for each direction of rotation; a single set of blades cooperative with both sets of nozzles; means for adjusting said ring relatively to its carrier to position either set of nozzles for connection with the steam supply; a catch 75 for each position of adjustment of said ring; a latch engageable selectively with said catches to lock the ring in adjusted position; and means for releasing said latch while the turbine is running.

11. A turbine comprising a rotary carrier; a nozzle ring encircling and rotatably connected to the carrier; two sets of reversely-arranged nozzles carried by said ring, one set for each direction of rotation; a toothed rim on said ring; a pinion mounted on a stationary part of the turbine and meshing with said rim to rotate the nozzle ring and thereby selectively connect either set of nozzles with the steam supply; and a stationary 90 blade ring encircling said nozzle ring and provided with a single set of blades for coaction with both sets of nozzles.

12. A turbine, comprising a rotary shaft; a carrier secured to said shaft to rotate therewith; a nozzle ring encircling said carrier to rotate both with and relatively to the same; two independent sets of nozzles carried by said ring, one set for each direction of rotation; blades, against which the 100 motive fluid is discharged by said nozzles, cooperative with the nozzles to produce the rotation of the carrier; and means for rotating the nozzle ring on said carrier to connect either set of nozzles with the motive 105 fluid supply or to shut off both sets therefrom.

13. A turbine, comprising a rotary shaft; a carrier secured to said shaft to rotate therewith; a nozzle ring encircling said carrier to rotate both with and relatively to the same; two independent sets of nozzles carried by said ring, one set for each direction of rotation; blades, against which the motive fluid is discharged by said nozzles, cooperative with the nozzles to produce the rotation of the carrier; means for rotating the nozzle ring on said carrier to connect either set of nozzles with the motive 110 fluid supply or to shut off both sets therefrom; and means for locking said ring in any one of its three positions.

14. A turbine, comprising a rotary shaft; a carrier secured to said shaft to rotate therewith; a nozzle ring encircling said car- 115

rier to rotate both with and relatively to the same; two independent sets of nozzles carried by said ring, one set for each direction of rotation; blades, against which the motive fluid is discharged by said nozzles, cooperative with the nozzles to produce the rotation of the carrier; means for rotating the nozzle ring on said carrier to connect either set of nozzles with the motive fluid supply or to shut off both sets therefrom; 10 a catch for each of the three positions of the ring; and a latch engageable selectively with said catches to lock the ring in any selected one of said positions.

BENOY BHUSHAN RÄHÄ.
